CIGAR DISPLAY DEVICE AND CLAMP FOR ASSEMBLING THE SAME

Filed Dec. 12, 1922

Inventor:
Daniel A. Gallagher
by *James C. Lamb*
his Attorney.

UNITED STATES PATENT OFFICE.

DANIEL A. GALLAGHER, OF CLEVELAND HEIGHTS, OHIO.

CIGAR-DISPLAY DEVICE AND CLAMP FOR ASSEMBLING THE SAME.

Application filed December 12, 1922. Serial No. 606,391.

To all whom it may concern:

Be it known that I, DANIEL A. GALLAGHER, citizen of the United States of America, and resident of Cleveland Heights, in the county of Cuyahoga, in the State of Ohio, have invented a certain new and useful Improvement in Cigar-Display Devices and Clamps for Assembling the Same, of which the following is a true and exact description, reference being had to the accompanying drawings, which form a part thereof.

My invention relates to a cigar display device whereby two cigar boxes are clamped together in such a way as to form an inclined display device well adapted to be set upon the cigar dealer's case and, also, my invention relates to the clamping device by means of which the cigar boxes are held in properly assembled relation.

The nature of my improvements will be best understood as described in connection with the drawings in which they are illustrated and in which—

Figure 1 is a perspective view showing the display device in assembled position, and

Figure 2 is a perspective view of the clamping mechanism and coupled glass lid, which forms a part thereof, in its most approved form.

A and B indicate the two cigar boxes to be coupled together into a display device. A' is the lid of a lower box A which is turned back against its rear side, A², as shown in Fig. 1 and against which the front side B² of the rear box B is abutted. C, C, are clamps of U form fitted over the sides A² and B² of the abutted boxes. As shown, these clamps are formed with perforations C' and C² in their tops through which perforations C² pass the bent eyes D', D', of a spacing rod D and through which perforations C', C', pass the bent eyes E', E', of the arms E, E, which are formed with fingers F, F, at their lower ends adapted to extend under the bottoms of the coupled boxes as shown in Fig. 1, thereby clamping the boxes in aligned position. The arms E preferably extend down in the spaces H, H, formed between the abutted boxes and the fingers F, as is shown, straddle the lid A' when they are in operative position.

By preference I hinge on the rod D by hinges G, G, a metal frame G' in which is

held the glass lid G² which covers the open box A. By preference also, and by means of clips I, I, secured to the lid B' of the rear box B, I secure to this lid a metallic frame I' supporting a glass lid I² which normally covers the open top of the other box but this device forms no part of my invention.

Having now described my invention, what I claim as new and desire to secure by Letters Patent, is:

1. A clamp for securing two cigar boxes together in aligned relation consisting of U shaped clamping means adapted to extend over the edges of abutted boxes in combination with an arm secured to said movable clamping means and having clamping fingers at its other end adapted to extend under the bottoms of the boxes and hold them in aligned position.

2. A clamp for securing two cigar boxes together in aligned relation consisting of two U shaped clamps adapted to extend over the edges of abutted boxes in combination with a spacing wire connecting the clamps together, and movable arms attached to each clamp and carrying clamping fingers adapted to extend under the bottoms of the boxes and hold them in aligned position.

3. A clamp for securing two cigar boxes together in aligned relation consisting of U shaped clamping means adapted to extend over the edges of abutted boxes in combination with a glass lid hinge connected to the clamping means and movable arms attached to the clamping means and carrying clamping fingers adapted to extend under the bottoms of the boxes and hold them in aligned position.

4. A cigar display device consisting of two cigar boxes one having its hinged lid folded back against its rear side and the other having its front side abutted against said folded back lid, in combination with U shaped clamping means fitting over the tops of the adjacent sides of the aligned boxes and arms hinged to said clamping means extending downward from the outer edge thereof and carrying fingers which extend below the bottoms of the abutted boxes on each side of the folded back lid.

DANIEL A. GALLAGHER.
